UNITED STATES PATENT OFFICE.

JOHN COLLOM, OF IDAHO SPRINGS, COLORADO TERRITORY.

IMPROVEMENT IN ORE-SEPARATORS.

Specification forming part of Letters Patent No. **146,168**, dated January 6, 1874; application filed July 19, 1873.

To all whom it may concern:

Be it known that I, JOHN COLLOM, of Idaho Springs, in the county of Clear Creek and Territory of Colorado, have invented a new and Improved Ore-Grading Machine, of which the following is a specification:

My invention consists of two or more grading-sieves in the upper portion of a tank of water having appropriate discharge-passages for different grades of material escaping from the sieves, which are actuated in the water by suitable mechanism, and also having a washing attachment so arranged that currents of water are caused to flow upward against the descending currents of ore and separating the "slime" water from the coarser particles, and causing it to flow with the fine particles of ore into another tank, in which is a siphon-pipe adapted to collect that which is sufficiently heavy to settle to the bottom of the water in said tank and convey it to the receptacle for it.

Figure 1 is a transverse sectional elevation of my improved ore-grading machine taken on the line *xx* of Fig. 2. Fig. 2 is a sectional elevation taken on the line *yy* of Fig. 1, and Fig. 3 is a sectional elevation of Fig. 1 on the line *zz*.

Similar letters of reference indicate corresponding parts.

A represents a water-tank, which is preferably made with two inclined sides and vertical ends, and has a hopper, B, inside, with a narrow slotted opening, C, at the bottom; also, an inclosed escape-passage, D, leading from the opening C at the bottom of the hopper up over the top of the hopper A into another hopper, E. F and G represent a couple of grading-sieves mounted on a shaking shoe, H, in the upper portion of the hopper A, which is actuated by a crank-shaft, I. The crushed ore is discharged, together with a stream of water, upon the upper end of the upper sieve. The coarse matters escaping off the lower end of sieve F pass out through the side of the hopper by the spout J, and those from sieve G escape by the spout K, while those falling through sieve G, also through the opening C, escape by the spout K'. In order to separate the slime-water and the lighter particles, I attach a washing apparatus, consisting of the water tank or box L,

into the top of which a supply of fresh water is caused to flow, and from which the water is caused to flow into tank A through the passages M N O, against the streams of ore, so as to separate the fine particles and slime-water from the larger and heavier grains, and carry them up through passage D into tank E. The water which enters at O encounters the falling ore at the passage C, and there separates the light matters. All these passages for admitting water to the tank A are provided with a regulating valve, P, by which the currents are regulated, as required.

In practice the spouts J, K, and K' discharge into water-tanks in which the water-level is kept about as high as that in tank A, so that the streams flowing into tank A are not carried off with the ore. Any number of grading-sieves may be employed in a gang, and any number of grades can be made.

In the tank B, to which the slime-water and light particles of ore are carried, there is a siphon-pipe, Q, connected with a long perforated pipe, R, in the angle at the bottom of the tank, which collects the particles which are heavy enough to settle, and the siphon carries them out of the tank into the proper receptacle. The part V of the siphon outside of the tank E is made of flexible substance, so that it can be put inside of the tank to be filled for setting the siphon in operation.

Having thus described my invention, I claim as new and desire to secure by Letters Patent—

1. The combination of a set of inclined submerged grading-sieves, a water-tank, and apparatus for actuating the sieves, substantially as specified.
2. The combination of means for injecting currents of fresh water, and the escape-passage D with the submerged sieves, substantially as specified.
3. The inverted T-shaped siphon-pipe, combined with a V-shaped receiving-tank, E, for the slime-water, substantially as specified.
4. The said siphon-pipe, provided with a flexible portion, V, substantially as specified.

JOHN COLLOM.
